UNITED STATES PATENT OFFICE.

JAMES H. DYETT, OF BUFFALO, NEW YORK, ASSIGNOR TO HARD MANUFACTURING CO.,
OF BUFFALO, NEW YORK.

FOLDING COT.

1,360,201.

Specification of Letters Patent. Patented Nov. 23, 1920.

Application filed September 29, 1917. Serial No. 193,912.

To all whom it may concern:

Be it known that I, JAMES H. DYETT, a citizen of the United States, residing at Buffalo, in the county of Erie and State of New York, have invented a new and useful Improvement in Folding Cots, of which the following is a specification.

This invention relates more particularly to folding or camp cots or beds of the sort which are used in the army and comprise a bed bottom formed by a piece of canvas or other suitable fabric or material, and a supporting frame therefor which is adapted to be folded into a compact bundle, of a length substantially one-half that of the cot in which the side rails and legs of the cot all lie substantially parallel close to each other.

The object of this invention is to produce a folding cot or bed of this type in which the frame is composed of metal tubes or pipes which are arranged and connected so as to insure an especially strong and rigid cot or bed, but which is nevertheless adapted to be folded into a compact bundle as stated, and is of simple, light and inexpensive construction.

In the accompanying drawings:—

Figures 1, 2 and 3 are respectively a side elevation, a plan view and an end elevation of a folding cot or bed embodying the invention.

Fig. 4 is an enlarged view of the frame folded, the bottom fabric being omitted to avoid confusion.

Fig. 5 is an end elevation of the cot showing the same partially collapsed with the side rails close together.

Fig. 6 is a section on an enlarged scale, on line 6—6, Fig. 1, showing the connection between one of the end legs and the side rails.

Fig. 7 is a longitudinal section of said connection partially folded.

Fig. 8 is a longitudinal section showing the connection between one of the intermediate legs and the side rail sections.

Fig. 9 is a sectional plan view showing the connection between one of the end and side rails.

Fig. 10 is a section on line 10—10, Fig. 5, showing one of the leg joints.

The cot or bed frame comprises two side rails each composed of two sections 1 and 2 which are connected so as to fold over one

upon the other, detachable end rails 3 which connect the ends of the side rails, and end and intermediate pairs of folding crossed legs which are hinged to the side rails to fold substantially parallel therewith. The legs of each pair are pivoted to each other between their ends to assume a substantially X form when in supporting position. The sections 1 and 2 of the side rails, the end rails and the legs are all preferably formed of metal pipes or tubes. 4 is the bottom fabric. This is provided at its side edges between the end and middle legs with pockets or hems 4^a through which the side rail sections extend, and at its ends with pockets or hems 4^b through which the end rails extend for stretching or holding the bottom fabric in supporting position on the frame.

The two sections 1 and 2 of each side rail are pivoted near their adjacent ends to a T-head 6 on the upper end of one leg of the intermediate pair of legs 5, 5. This head 6, see Fig. 8, preferably consists of a malleable casting having a socket 7 in which the upper end of the tubular leg 5 is rigidly secured in any suitable manner, and parallel spaced side plates 8 between which the sections 1 and 2 of the side rails are suitably pivoted, as by rivets or pins 9. The end portions of the side rail sections 1 and 2, when in aligned supporting position extend toward each other between the side plates of the head 8 with their inner ends abutting between the pivots 9. These end portions of the side rail sections are preferably flattened somewhat at opposite sides, as shown at 10, so as to bear flat against the inner faces of the sides of the head 6 of the leg substantially throughout the length of the head. The side rail sections thus have flat bearings of considerable area against the sides of the head 6 and the sections are thus held rigidly in alignment and prevented from twisting in the head on their pivots. The upper end of each leg tube 5 also preferably extends up through the socket 7 into the space between the sides of the head 6 and is concaved, as shown at 11, to form a seat for the convex under sides of the inner ends of the side rail sections. This aids the sides of the head in holding the side rail sections rigidly in alignment. The ends of the side rail sections can practically abut against each other with-

out interfering with their folding movement, since the ends are hollow and one end can swing in the cavity of the other end when holding the sections as indicated in 5 Fig. 8.

12 represents heads rigidly secured on the upper ends of the legs 13 of the end pairs of legs and hinged to the end portions of the side rails to permit the legs to be folded 10 from the supporting position shown in Figs. 1-3, over to the folded position shown in Fig. 4, in which the legs lie substantially parallel with the upper faces of the side rail sections. Each of the heads 12 preferably consists of a malleable casting having a socket 14 in which the upper end of the leg tube is rigidly secured, as by a rivet 15, or otherwise, and two parallel spaced side plates 16 which straddle and are suitably 15 pivoted, as by a rivet 17, to the end portion of the side rail section. The side plates of the heads 12 extend from the upper ends of the legs toward the ends of the side rails, so that when the legs are in the supporting 20 position the side plates of the head embrace the opposite sides of the side rail sections for a considerable distance and permit the legs to swing around the ends of the side rails from their supporting position to their 25 folded position. The end portions of the side rails are preferably pressed out of circular shape or flattened at opposite sides, as shown at 18, Fig. 6, so that when the legs are in supporting position the sides 16 of 30 the heads 12 will bear substantially throughout their length flat against the opposite sides of the side rails. The upper ends of the tubular legs also preferably extend up through the sockets 14 between the sides of 35 the heads 12 and are provided with concaved seats 19 adapted to engage the convex undersides of the side rails, as before explained in connection with the middle legs. 40 This construction, while permitting the free 45 swinging of the legs from their supporting to their folded position insures a very rigid and strong connection between the legs and the rails which prevents any lateral swaying motion or twisting of the side rails relative to the legs and prevents excessive pressure of the side rails on the heads which would otherwise act to distort or bend the heads whereby the rails would sag or be lowered relative to the legs. In this construction the greater the weight or pressure 50 on the side rails the more secure will be the connections between the rails and the legs and greater rigidity of the cot will be had. 55 The two legs of each pair are preferably 60 bent at 20 between their ends, where they cross so that the lower and upper portions of each leg are offset relatively to or out of line with each other, thereby permitting the legs of each pair to lie substantially parallel 65 with each other when collapsed, as shown in

Fig. 5. The bent or intermediate parts of the legs of each pair are also preferably flattened or pressed out of round, as shown in Fig. 10, thus providing substantially flat faces 21 which bear against each other. 70 These flat faces bearing against each other resist the tendency of the legs to twist relatively to each other on their connecting pivots 22 and greatly relieve the strain on the pivots. The flattening of the crossing 75 parts of the legs also locates the two legs of each pair substantially in the same plane.

Each of the end rails 3 of the frame preferably consists of a straight metal tube or pipe provided near its opposite ends with 80 holes 23^a adapted to receive pins or studs 23 projecting out from the ends of the side rails. These pins or studs can be formed on plugs 24 rigidly secured in any suitable manner in the ends of the side rails or can 85 be otherwise formed on or secured to the side rails. In setting up the cot for use the end rails are slipped through pockets or hems 4^b at the ends of the canvas or other bed bottom fabric or material, and are then 90 secured in place at the ends of the side rails by engaging the pins or studs on the side rails in the holes in the end rails. The bottom fabric is made of such length that it is necessary to stretch it taut in order to engage 95 the end rails on the ends of the side rails. The bed bottom or canvas strip thus draws the end rails toward each other and holds them firmly in place on the studs on the side rails. In folding the cot the end 100 rails are first disengaged from the studs at the ends of the side rails and are then slipped out of the hems or pockets at the ends of the bed bottom fabric. The cot frame can then be folded, the bottom fabric 105 remaining in place on the side rails and being folded with the frame.

To fold the cot the end and intermediate legs are collapsed or swung on their pivots to bring the opposite side rails close together, as shown in Fig. 5. The end legs can then be swung around the ends of the side rails from their supporting positions to positions substantially parallel with and at the upper sides of the side rails and the sections 1 and 2 of the side rails can be folded downwardly to opposite sides of the intermediate pair of legs substantially parallel therewith. The legs and side rail sections will then all occupy positions close together 115 and substantially parallel as shown in Fig. 4.

I claim as my invention:—

1. In a folding cot, a two-section side rail, a supporting leg therefor, a single-piece metallic head for said leg, pivots connecting 125 the sections of said side rail with said head whereby in open position of the cot adjacent ends of the rail sections abut and present a continuous rail member, said leg extending into said head and supporting the abutting 130

ends of said rail sections, said rail section ends being seated upon and completely covering the entire upper end of said leg.

2. In a folding cot, a folding frame comprising side rails; crossed supporting legs therefor, a single-piece metal head for each of said legs comprising a socket in which the upper portion of the leg fits and is rigidly secured and spaced side plates which are integral with and extending from the socket parallel with and straddle one of said side rails, said side rails having flat faces which bear against flat faces on said side

plates of the heads, said legs extending up through said sockets and terminating in said heads and above said sockets in concave ends in which the side rails are seated, and pivots connecting said side plates to said side rails to permit the legs to fold relatively to the side rails.

Witness my hand this 25th day of September, 1917.

JAMES H. DYETT.
